(57) **CLAIM**

The ornamental design for a mixing machine, as shown and described.

DESCRIPTION

FIG. 1 is a front-right side perspective view of a mixing machine showing my new design;

FIG. 2 is rear-right side perspective view thereof;

FIG. 3 is a front-left side perspective view thereof; and,

FIG. 4 is a rear-left side perspective view.

The broken lines shown in the drawings are for illustrating portions of the mixing machine that form no part of the claimed design.
